Primary Examiner — Catherine S Posthauer

(74) *Attorney, Agent, or Firm* — Young Basile Hanlon & MacFarlane, P.C.

(57) **CLAIM**

The ornamental design for a lid for a cup, as shown and described.

DESCRIPTION

FIG. 1 is a front view of a first embodiment of a lid for a cup of my new design;

FIG. 2 is a rear view thereof;

FIG. 3 is a left view thereof;

FIG. 4 is a right view thereof;

FIG. 5 is a top view thereof;

FIG. 6 is a perspective view thereof;

FIG. 7 is a reference perspective view thereof in a first environment; and

FIG. 8 is a reference perspective view thereof in a second environment.

FIG. 9 is a front view of a second embodiment of a lid for a cup of my new design;

FIG. 10 is a rear view thereof;

FIG. 11 is a left view thereof;

FIG. 12 is a right view thereof;

FIG. 13 is a top view thereof;

FIG. 14 is a perspective view thereof;

FIG. 15 is a reference perspective view thereof in a first environment; and,

FIG. 16 is a reference perspective view thereof in a second environment.

Broken lines in the drawings represent an unclaimed environment of a cup and form no part of the claimed design. The drawings include stipple shading to show contrast of materials.

1 Claim, 16 Drawing Sheets
